(57) **CLAIM**

The ornamental design for a kickboard, as shown and described.

DESCRIPTION

FIG. 1 is a front perspective view of a kickboard, showing our new design;

FIG. 2 is a rear perspective view of the kickboard;

FIG. 3 is a top view of the kickboard;

FIG. 4 is a bottom view of the kickboard;

FIG. 5 is right side view of the kickboard;

FIG. 6 is a left side view of the kickboard;

FIG. 7 is a front view of the kickboard; and,

FIG. 8 is a back view of the kickboard.

The broken lines depict portions of the kickboard that form no part of the claimed design.

1 Claim, 6 Drawing Sheets
